CLAIM

Oct. 16, 2015 (JP) 2015-022909

The ornamental design for a steering wheel for a motor vehicle, as shown and described.

(51) **LOC (10) Cl.** **12-16**

DESCRIPTION

(52) **U.S. Cl.**

USPC **D12/176**

(58) **Field of Classification Search**

FIG. 1 is a front perspective view of a steering wheel for a motor vehicle, showing our new design;

USPC D12/175, 176; 74/552, 558, 558.5

FIG. 2 is a front view thereof;

CPC B60R 21/203; B60R 21/05; B62D 1/04

FIG. 3 is a rear view thereof;

See application file for complete search history.

FIG. 4 is a right side view thereof;

(56) **References Cited**

FIG. 5 is a left side view thereof;

U.S. PATENT DOCUMENTS

FIG. 6 is a top view thereof; and,

D635,900 S * 4/2011 Anzi D12/176

FIG. 7 is a bottom view thereof.

D640,619 S * 6/2011 Araki D12/176

The lightened portion of the steering wheel for a motor vehicle shown in FIG. 3 represents where the steering wheel attaches to a portion of a motor vehicle and it is not seen during ordinary use of a motor vehicle and is not part of the claimed design.
